[57] CLAIM

The ornamental design for a base for a telephone set, substantially as shown and described.

DESCRIPTION

FIG. 1 is an isometric view of the base for a telephone set; showing our new design;

FIG. 2 is a top plan view of the base for a telephone set; FIG. 3 is a front elevational view of the base for a telephone set;

FIG. 4 is a right elevational view of the base for a telephone set;

FIG. 5 is a left elevational view of the base for a telephone set; and

FIG. 6 is a back elevational view of the base for a telephone set.

The broken lines representing the handset are shown for illustrative purposes only.
